Inventor:

Andrerr J. Halsey.
by his Attorney, O. Drake,

UNITED STATES PATENT OFFICE.

ANDREW J. HALSEY, OF NEWARK, NEW JERSEY.

CUFF ADJUSTER AND SUPPORT.

SPECIFICATION forming part of Letters Patent No. 252,102, dated January 10, 1882.

Application filed July 14, 1881. (No model.)

To all whom it may concern:

Be it known that I, ANDREW J. HALSEY, a resident of Newark, in the county of Essex and State of New Jersey, have invented certain new and useful Improvements in Cuff Adjusters and Supporters; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to enable what are known as "reversible" cuffs to be more readily adjusted upon the wrist of the wearer and to secure the same at any point thereon that the wearer may desire, as will be further and more definitely explained hereinafter.

Heretofore cuffs secured upon the arm or wrist by elastic bands connected therewith had connecting-pieces, or loops of elastic cord or other material, which connected said cuff to said band. When arranged upon the arm the said band and the connecting-pieces came considerably above the cuff and were exposed to view. The device, being complicated, was very liable to get out of order, and very susceptible to wear, so that very soon the said exposed parts became unsightly, as will be clearly seen. By my improved device these defects have been remedied, and the adjustment of the parts upon the wrist or arm is more speedily accomplished, and the operation of the device otherwise more satisfactory.

The invention consists in the arrangement and combinations of parts herein set forth, shown, and finally embodied in the claim.

Referring to the accompanying drawings, in which similar letters of reference indicate like parts in each of the several figures, Figure 1 is a perspective view of a cuff to which my improvement has been applied, and Fig. 2 is an end representation, more clearly showing the relation of parts.

In carrying out my invention I form the cuff A in the usual manner, with button-holes b c therein, into one of which is secured the usual button, d, and the other is adapted to receive a button or stud. I then form a band, B, preferably elastic, and provide the same with a button or stud, a, or other device for the purpose, which said button or stud may either be inserted into a button-hole in said band or be sewed or otherwise secured thereto. Said band B and cuff A are then combined and arranged in relation to one another as in the manner shown, said band being in that part of the cuff through which the wrist is first inserted.

In arranging the improved device upon the band, the band B is taken in one hand and drawn over the other the desired distance and allowed to contract around the wrist or arm. The cuff must of course follow the band, as will be evident. It is intended that the band shall be of a size to fit the wrist snugly without binding or interfering with the comfort of the wearer.

I am aware that elastic bands have been used heretofore upon the arm to hold the cuff in position, and therefore I do not wish to be understood as claiming this feature, broadly; but,

Having described my invention, what I claim, and wish to secure by Letters Patent, is—

The combination, with the cuff, of the elastic band, arranged and secured within the said cuff, and the button or stud a, passed through perforations in said cuff and band and holding said parts intact, the whole being arranged and adapted to operate substantially as and for the purposes set forth and shown.

In testimony that I claim the foregoing I have hereunto set my hand this 5th day of July, 1881.

A. J. HALSEY.
